UNITED STATES PATENT OFFICE.

JACOB R. FRY, OF NEW YORK, N. Y., ASSIGNOR TO WESTERN ELECTRIC COMPANY, INCORPORATED, OF NEW YORK, N. Y., A CORPORATION OF NEW YORK.

ALTERNATING-CURRENT RELAY.

Application filed May 11, 1922. Serial No. 560,087.

This invention relates to relays designed to selectively respond to currents of a desired frequency.

An object of the invention is to make an alternating current relay which responds with certainty to currents of a desired frequency even though such currents be very feeble, but does not respond to aperiodic currents or currents of other frequencies.

Other objects of the invention are to improve the adjusting means for the pole pieces, as well as the adjusting means for the contacts of a relay.

More specifically, the invention relates to an extremely sensitive alternating current relay of the vibrating reed type in which the vibrating reed is actuated by a pair of magnets placed on either side of the free or vibrating end of the reed. Such a relay may be used to advantage on long telephone lines for signaling purposes, wherein the current is frequently much attenuated when it reaches a repeater or a terminal station, and consequently a very sensitive instrument is required to respond thereto. The pole pieces and coils of the relay magnets are so mounted that the air gap between the poles may be varied to a very minute degree. This method of adjustment serves as a means for compensating for the natural period of vibration of the reed, when, due to variations in its construction, its period is below or above the frequency to which the relay is to respond.

In the drawings, Fig. 1 shows a preferred embodiment of the relay in perspective, while Fig. 2 is a side elevation of the relay, parts thereof being shown in section, and Fig. 3 is a plan view, also partially in section, of one end of the relay showing the means for adjusting the pole pieces and the contact members.

Referring to the drawings in detail, a relay having a base plate 1 is yieldingly mounted upon a flanged sheet metal support 2 by means of rubber sponges 3. Two of these rubber sponges are held in alignment on either side of the metallic base 2 by means of ears 21 punched from the support 2, and are secured to the base plate 1 of the relay by means of a washer 22 and a stud screw 23 which terminates in the relay base 1. Two pairs of sponges complete the resilient mounting.

A terminal block 4 secured to one end of the base 2 is provided with a series of plugs 5, thus adapting the relay for rack mounting, the rack (not shown) being provided with a plurality of jacks which are designed to receive the plugs. A flange carrying a projecting portion 6 is provided at the opposite end of the base 2 to facilitate handling the relay.

An armature supporting block of metal 7 is attached to one end of the base plate 1 and has secured thereto one end of a reed or armature 8, the other end of which is free to vibrate within the limits hereinafter described. A U-shaped bar 11 rests in the transverse groove 12 in the base plate 1 and is held in place by one end of a permanent bar or plate magnet 17, the other end of which engages a groove 24 in the block 7. The magnet 17, which is in a magnetic circuit with the armature 8, is secured to the base plate 1 by means of stud screws 25. The up-turned ends of U-shaped member or bar 11, are bifurcated and are in addition provided with bearings to receive cylindrical pole pieces 13 upon which magnetizing coils 9 and 10 are mounted. An additional bearing for the pole pieces is provided between the adjacent parallel brackets 14 secured to the bifurcated ends of the member 11. Adjusting members 15, consisting of wheels having holes punched in their peripheries to facilitate their turning, are threaded to pole pieces 13 intermediate the up-turned ends of the member 11 and the parallel brackets 14. By rotating member 15, it is possible to vary the position of the pole pieces 13 and to draw the electromagnetic coils toward or away from the up-turned ends of the member 11. Inasmuch as the pole pieces 13 are held against rotation in their bearings in the member 11 by means of keys or pins 32 which are integral with the pole pieces and extend into the bifurcation of their supports, it is possible to vary the positions of the magnets without rotating them. Adjustable stud screws 18 are provided in the upper ends of the member 11 in order to lock the pole pieces in their adjusted position.

A resilient spring 26 is provided for making contact with the reed 8 and an adjusting means is also provided for controlling the functions of the spring 26 in relation

to the reed when vibrating. This adjusting means consists of a resilient spring 35, projections 36 thereon limiting the movement of the spring 26 in one direction and 6 an adjusting screw 27. The resiliency of the spring 26 by itself limits to a certain extent the amplitude of vibration of the reed, while the relation of the make to the 12 break period of the contact between the reed 8 and the spring 26 may be varied by the operation of the screw 27. The screw 27 may also be used for controlling the relation of the spring 26 to the reed 8 in such a manner as to permit the reed to vibrate 18 at its natural frequency with the least possible interference from spring 26. This latter adjustment may be of considerable importance when the operating characteristics 24 of the reed are such as to make it particularly sensitive to interference that may be caused by the amplitude limiting tendency of the spring 26. The adjustable screw 27 is held in a bifurcated post 19 and locked thereto by means of an adjusting stud screw 25 20. An adjusting knob 28 has a calibrated periphery and has associated with it circumferential shield 29 which permits a reading of its adjustment. A second adjustable screw 30 which is held in a bifurcated post 30 31, serves as a back stop to limit the whip or temporary distortion of the armature when a current impulse of excessive strength causes the relay to suddenly pull over its armature without vibrating it.

25 What is claimed is:

1. In combination, a base, a block mounted thereupon at one end of said base, a supporting means at the other end of said base, a permanent bar magnet between said block and said supporting means, a tuned reed having one end thereof secured to said block, a pair of spaced magnetic cores mounted upon said supporting means and movable relatively thereto, said cores serving to actuate the free end of said reed, and means associated with said supporting means for adjusting the distance between said cores.

2. In combination, a base, a block mounted on one end of said base, a supporting member fixed at the other end of said base, a magnetic pole piece mounted on said support, a permanent magnet connecting said block and said supporting member, a vibrating armature parallel to said magnet fixed 55 at one end to said block and with its free end in spaced relation to said pole piece, an adjusting means for said armature to limit the vibratory movement thereof, and an adjusting means for said pole piece to vary its position in relation to said armature.

3. In combination, a base, a block mounted on one end of said base, a supporting member having two parallel arms mounted 60 at the other end of said block, a pole piece

secured to each of said arms, coils on said pole pieces, a permanent magnet connecting said block and said supporting member, a flexible reed fixed at one end to the block and with its free end in a position between 79 said pole pieces, means to regulate the vibratory movement of said reed between said pole pieces, and means to adjust the distance between the pole pieces and the reed.

4. In combination, a base, a block mounted thereon, a supporting member having two parallel arms mounted on said base away from said block, a pole piece secured to each of said arms, coils on said pole pieces, a permanent magnet connecting said block and said supporting member, a flexible reed fixed at one end to the block and with its free end extending between said pole pieces, means to regulate the vibratory movement of said reed between said pole pieces comprising a flexible contact and an adjusting means to regulate the tension thereof, and separate means for adjusting the distance between the pole pieces and the reed.

5. A relay comprising a base, a block mounted thereon, a comparatively long armature secured at one end to said block in a position parallel to the base, a stationary support on said base adjacent the free end of the armature, a permanent magnet of approximately the same length as the armature connecting the block and the support, and arranged in a position parallel to the base, a pole piece mounted upon said support in spaced relation to the free end of the armature, and means associated with said pole piece for varying the distance between the pole piece and the free end of the armature.

6. A relay comprising a base, a block mounted thereon, a comparatively long armature secured at one end to said block in a position parallel to the base, a stationary support on said base adjacent the free end of the armature, a permanent magnet of approximately the same length as the armature connecting the block and the support, and arranged in a position parallel to the base, a threaded pole piece mounted upon said support in spaced relation to the free end of the armature, and means cooperating with said threaded pole piece for varying the distance between the pole piece and the free end of the armature.

7. A relay comprising a base, a block mounted thereon, a comparatively long armature secured at one end to said block in a position parallel to the base, a unitary U-shaped bracket mounted upon said base adjacent the free end of the armature, a permanent magnet of approximately the same length as the armature connecting the block and the bracket and located in a position parallel to the base, a pair of spaced magnetic cores mounted on said bracket and spaced from either side of the free end of

said armature, coils upon each of said cores, and means for shifting said cores to vary the distance between them.

8. A relay comprising a base, a block 5 mounted thereon, a comparatively long tuned reed secured at one end to said block in a position parallel to the base, a unitary U-shaped bracket upon said base adjacent the free end of the reed, a permanent magnet of 10 approximately the same length as the reed connecting the block and the bracket and lo-

cated in a position parallel to the base, a pair of spaced electrically energized magnetic cores mounted on said bracket and spaced from either side of the free end of 15 said reed, said cores serving to actuate said reed, and means for shifting said cores to vary the distance between them.

In witness whereof, I hereunto subscribe my name this 4th day of May, A. D. 1922.

JACOB R. FRY.
